Specification for Design.

Patented Apr. 26, 1910.

Application filed February 28, 1910. Serial No. 546,207. Term of patent 7 years.

To all whom it may concern:

Be it known that I, PAUL R. ZINSER, a subject of the Emperor of Germany, and resident of Cincinnati, county of Hamilton, State of Ohio, have invented a certain new, original, and ornamental Design for Lugs for Coffins or Caskets, of which the following is a specification, reference being had to the accompanying drawing, forming a part thereof.

The figure is a front elevation of a lug for a coffin or a casket, showing my new design.

I claim:

The ornamental design for a lug for a coffin or a casket, as shown.

PAUL R. ZINSER.
